UNITED STATES PATENT OFFICE.

GEORGE A. BENNETT, OF PRAHRAN, MELBOURNE, AND FREDERICK B. A. KIRSTEN, OF BALWYN, MELBOURNE, VICTORIA, AUSTRALIA.

RENEWABLE OR LOOSE LEAF BOOK.

1,406,166.

Specification of Letters Patent. Patented Feb. 14, 1922.

Application filed November 11, 1920. Serial No. 423,390.

To all whom it may concern:

Be it known that we, GEORGE ALFRED BENNETT, a subject of the King of Great Britain and Ireland, and a resident of the 5 city of Prahran, a suburb of the city of Melbourne, in the county of Bourke, State of Victoria, Commonwealth of Australia, and FREDERICK BENJAMIN ADOLPH KIRSTEN, a subject of the King of Great Britain and 10 Ireland, and a resident of the postal district of Balwyn, a suburb of the city of Melbourne, in the county of Bourke, aforesaid, have invented certain new and useful Improvements in Renewable or Loose Leaf 15 Books, of which the following is a specification.

This invention relates to books having renewable or interchangeable leaves and more particularly to sales books, pocket books and 20 other comparatively small books of that type. It will be evident from the following description, however, that the invention is not by any means limited to such comparatively small books but may be applied to other 25 books of various kinds and sizes.

The object of the invention is to provide an extremely simple and inexpensive means for retaining the leaves of a book within its cover in such a manner that they may be 30 readily withdrawn and replaced or renewed as desired.

The invention is primarily applicable to books having single loose leaves adapted to be withdrawn and replaced independently 35 of each other.

But in order that this invention may be better understood reference will now be made to the accompanying sheet of drawings which is to be taken as part of this 40 specification and read herewith:—

Figure 1 is a perspective view of a book cover having a leaf holder, in accordance with the invention, attached thereto.

Figure 2 is a cross section.

Figure 3 is a perspective view of a block of single loose leaves retained together by a metallic binding wire or tape and also adapted for use with the present invention.

Figure 4 shows in section a modified arrangement of the block of leaves and binding wire seen in Figure 3.

Figure 5 is a section on line B—B of Figure 3.

Figure 6 is a cross section showing the

block of loose leaves seen in Figures 3 and 4 retained within the leaf holder.

According to the invention the book cover 2 is attached to the rear of a leaf holder 3 preferably formed of spring metal of substantially U shape or C shape in cross section as seen in Figure 2. The leaf holder thus forms a channel 4 having an open mouth 6 through which the leaves are passed lengthwise into or out of the holder. The sides of this mouth form opposite jaws between which the leaves are held. These opposite jaws may be provided with outward edges 7, as seen in Figs. 1, 2 and 6, which prevent cutting or wearing of the leaves when the latter are being introduced or withdrawn.

One end of the channel 4 may, if desired, be bridged by tongues 8 or entirely closed to prevent the leaves being pushed too far along the holder, whilst the other end is entirely open as at 9 to allow of the introduction and removal of the leaves as hereinafter described.

The sides of the open mouth 6 at the open end 9 of the holder may be flared or diverge towards the adjacent end of the holder as indicated at 11 to facilitate the introduction of the leaves.

The leaf holder 3 may be retained to the cover 2 by any suitable means, for instance by a retaining wire 12 which passes through holes in the cover and the back of the leaf holder respectively.

A block of single loose leaves 24 may be employed with the leaf holder. These leaves are interchangeably bound together by a metallic binding tape or wire 26 passing through holes 27 or niches 30 in the leaves. The ends of the tape 26, which may normally spring outwards as shown in dotted lines in Figure 4 are turned down flat upon one of the outside leaves when introduced into the holder, as shown in full lines.

Such leaves are particularly useful for note books and the like and enable individual leaves to be withdrawn and replaced without tearing from the book. A block of leaves of this type is introduced lengthwise through the open end 9 of the leaf holder, the leaves being held firmly in place by the spring jaws or lips 7 which prevent them being withdrawn excepting lengthwise of the leaf holder.

It will be evident that the springy nature of the leaf holder enables it to accommodate itself to blocks of leaves of different thickness, as when leaves are removed or added, 5 the jaws at the sides of the open mouth 6 pressing against the leaves sufficiently tightly to retain them in place.

Having now fully described and ascertained our said invention and the manner in 10 which it is to be performed, we declare that what we claim is:—

15 The combination of a resilient leaf holder of channel section, open at at least one of its ends to permit the insertion or withdrawal of the leaves lengthwise; a block of single loose leaves inserted in the channel of the holder through said end and having opening therethrough adjacent its inner cor-

ners; and a spring binding tape having its central portion arranged against one face of 20 the block of leaves and its end portions inserted through said openings and projecting beyond the opposite face of said block, the projecting parts of said end portions having a tendency to spring outwards away from 25 each other and from the block but being pressed inwards toward said block consequent upon the insertion of the block in the holder.

In testimony whereof we affix our signatures.

G. A. BENNETT.
F. B. A. KIRSTEN.

Witness:
VICTOR J. KELSON.
